UNITED STATES PATENT OFFICE.

ROBERT SUCZEK, OF PHILADELPHIA, PENNSYLVANIA, ASSIGNOR TO C. H. WHEELER MANUFACTURING COMPANY, OF PHILADELPHIA, PENNSYLVANIA, A CORPORATION OF PENNSYLVANIA.

FLUID-COMPRESSING APPARATUS.

Application filed January 23, 1923. Serial No. 614,364.

To all whom it may concern:

Be it known that I, ROBERT SUCZEK, a citizen of the United States, residing in the city and county of Philadelphia, State of 5 Pennsylvania, have invented certain new and useful Improvements in Fluid-Compressing Apparatus, of which the following is a specification.

My invention relates to ejector apparatus 10 for compressing in a plurality of stages elastic fluid, such as air, gas, vapor, or a mixture of them, utilizable in any suitable system or relation, but more particularly intended for the withdrawal of elastic fluid 15 from a power plant steam condenser or the like, and raising the elastic fluid to suitably high pressure, as for example, atmospheric pressure.

In accordance with my invention, an 20 ejector of a series discharges into a so-called "inter" condenser, that is, an interstage condenser, and an ejector staged later in the series discharges into a so-called "after" condenser, in the same shell with the inter 25 condenser, the inter and after condensers being cooled by a plurality of cooling media flowing in independent passes or systems, one of the cooling media being, for example, condensate from the large or main condenser 30 and another of the cooling media being liquid, as colder water, from any other desired or suitable source, each of the plurality of cooling media serving to cool both the inter and after condensers, preferably in 35 counter-current flow or relation.

Further in accordance with my invention, two or more multi-stage ejector systems with their inter and after condensers are combined, the inter and after condensers 40 for the different ejector systems being disposed within the same shell or housing and subjected to different cooling media.

My invention resides in fluid compressing apparatus or combined ejector-condenser 45 structure of the character hereinafter described.

Some of the features of construction and combination herein disclosed are described in my prior applications Ser. No. 317,875, 50 filed August 16, 1919; Ser. No. 379,716 and Ser. No. 379,717, filed May 8, 1920.

For an illustration of one of the various forms my invention may take, reference is

to be had to the accompanying drawings, in which:

Fig. 1 is a vertical sectional view, some parts in elevation, through apparatus embodying my invention and taken on the line 1—1, Fig. 5.

Fig. 2 is a horizontal cross section, some parts in plan, on reduced scale, taken on the line 2—2 of Fig. 1.

Fig. 3 is a horizontal sectional view, some parts in plan, taken on the line 3—3 of Fig. 1.

Fig. 4 is a horizontal sectional view, some parts in plan, taken on the line 4—4 of Fig. 1.

Fig. 5 is a top plan view, on reduced scale, of the structure shown in Fig. 1.

Fig. 6 is a top plan view of the structure shown in Fig. 1, with the ejector apparatus removed.

Fig. 7 is a fragmentary vertical sectional view on the line 7—7 of Fig. 6.

Fig. 8 is a top plan view of the condenser shell with top tube sheet removed.

Fig. 9 is a bottom plan view of the condenser shell with the bottom tube sheet removed.

Fig. 10 is a top plan view of the bottom end box of the condenser.

Fig. 11 is a cross sectional view on the line 11—11 of Fig. 10.

Fig. 12 is a vertical elevational view, parts 85 in section, showing the ejector apparatus and its condensing structure in combination with a main condenser.

Fig. 13 is a vertical sectional view through the drain control or condensate draw-off 90 traps.

Fig. 14 is a sectional view of the same structure taken on the line 14—14 of Fig. 13.

Referring first to Fig. 5, there are shown two multi-stage ejector systems, each system comprising, in the example illustrated, two ejectors operating in tandem or staged relation. The first stage ejector of one pair is indicated at E and the second stage ejector at R. In the second system the first stage ejector is indicated at E¹ and the second stage ejector at R¹.

As shown more clearly in Fig. 1, at E, each of the first stage ejectors may be of any suitable type, in the example illustrated 105 of the so-called tubular type, comprising

the tubular diffuser D whose inlet is disposed in the suction chamber a, into which projects the nozzle structure N comprising one or more nozzles of the divergent expansion type for expanding elastic motive fluid, as steam, delivered thereto through the pipe b controlled by valve c.

Each of the second stage ejectors R, R¹ may be of any suitable type, and in the example illustrated is of the radial flow expansion nozzle type of the character disclosed in Letters Patent of the United States No. 1,282,595, to the nozzle structure of which steam is delivered through the pipe d, which is branched to the nozzle structures of the two ejectors R, R¹, the branches being controlled by the valves e, e¹, which control also the delivery of steam from the pipe d to the pipes b, b¹ leading to the nozzle structures of the first stage ejectors.

With these ejectors are combined the condenser structure K comprising the common or single housing or shell A, in which is disposed the heat transfer structure of an inter and after condenser for each of the ejector systems. The upper and lower ends of the shell A are closed by the tube sheets B and B¹, forming, respectively, the lower and upper end closure walls for the upper and lower end boxes F and F¹, respectively.

Between the peripheral wall of the upper box F and the three partition walls 1, 2 and 3 within the box F, forming a tight joint with the upper tube sheet B, is the chamber f, into which the diffuser D of the first stage ejector E discharges through the port or aperture 4 a mixture of motive fluid steam and air or other elastic fluid which has been entrained thereby in the suction chamber a and raised to higher pressure. Extending through the tube sheet B and terminating at their upper ends in the chamber f is a group of tubes g extending downwardly through the shell A through the lower tube sheet B¹ and discharging into the chamber h in the lower end box F¹, said chamber h being formed between the partitions 5 and 6 in the box F¹ making a tight joint with the lower tube sheet B¹. Communicating with the same chamber h is a group of tubes i, extending through the tube sheet B¹ and the shell A and the upper tube sheet B, and discharging into the chamber j in the upper box F formed between the periphery of said box and the aforesaid partition 2 and the partition 7, which makes a tight joint with the tube sheet B. The chamber j communicates through the passage k with the chamber m formed between the aforesaid partitions 1 and 3 and the partitions 8 and 9, which form a tight joint with the tube sheet B. Communicating at their upper ends with the chamber m is a group of tubes n, through which the ejector discharge passes downwardly into a chamber o in the lower

end box F¹, said chamber formed between the aforesaid partition 6, a continuation of the partition 5 and the partition 10. Communicating at their lower ends with the chamber 10 is a group of tubes p, through which the ejector discharge passes upwardly into the chamber q in the upper end box F, the chamber q being formed between the partitions 7, 9 and a continuation of the partition 8. The chamber q has a discharge outlet 11, through which the air or uncondensed component of the mixture discharged from the ejector E is delivered through the passage or conduit G delivering to the suction chamber of the second stage ejector R, which discharges a mixture of motive steam and the entrained air or other elastic fluid raised to still higher pressure, for example, to substantially atmospheric pressure or higher, through the port 12 into the chamber r in the upper box F formed between the periphery thereof and the partitions 13 and 14, extending to the tube sheet B and forming a tight joint therewith. Communicating with the chamber r is a group of tubes s, through which the ejector discharge passes downwardly into the chamber t in the lower end box F¹ formed between the aforesaid partition 5 and a continuation of the partition 6, said partitions forming a tight joint with the tube sheet B¹. The discharge then passes upwardly through the group of tubes u, which discharge into the chamber v in the upper box F formed between the partitions 1 and 13 and communicating with the chamber w, with which communicates the group of tubes x, through which the discharge passes downwardly into the chamber y in the lower end box F¹ formed between the partitions 5, 6 and 10, forming a tight joint with the tube sheet B¹. The discharge then passes upwardly through the group of tubes z into the discharge chamber I common to the two ejector systems, the chamber I having the port or outlet 15 through which the air raised to suitable pressure, as atmospheric pressure or pressure above or below atmospheric pressure, is discharged directly into the atmosphere or into any desired or suitable receptacle.

For the second ejector system comprising the ejectors E¹ and R¹ there are provided chambers and groups of tubes similar to and symmetrically arranged with respect to those described in connection with the first ejector system E, R. The chambers and groups of tubes for the second ejector system bear the same reference characters as those described in connection with the first ejector system, with the addition, however, of subscript numerals "1". And the partitions in the upper and lower boxes F and F¹ bear numerals similar to those described in connection with the first ejector system.

Associated with such of the groups of tubes

as may be suitable or desirable are drain tubes or pipes 17, Fig. 1, terminating at their upper ends flush with the upper surface of the tube sheet B, and provided at their lower ends with liquid seal traps or caps 18, whereby any condensate collecting on the tube sheet B is drained into chambers of the lower box F¹, the seals 18 being utilized to allow flow of condensate into the lower chambers without, however, equalizing the pressure between the upper and lower chambers. Structure of this nature is described in my prior application Ser. No. 317,875, filed August 16, 1919.

15 The condenser shell A is provided on its interior with partitions or baffle walls forming distinct passes or routes for different and independent cooling media, each cooling medium serving to cool the exteriors of the 20 tubes of both the inter and after condensers of both ejector systems.

The cooling medium of higher temperature, as condensate from the main condenser from which the ejectors exhaust air and un- 25 condensable vapors or gases, enters through the port or opening 19 and is divided into two streams flowing through the passages or conduits 20 adjacent the upper end of the shell A, and flows downwardly between and 30 around the tubes *i* and *i*¹ in a pass bounded by the shell A and the partitions 21, 22, of which 21 at its upper edge forms a tight joint with the lower side of the upper tube sheet B and at its lower end forms a tight 35 joint with the upper surface of the lower tube sheet B¹, while the partition 22 at its upper end forms a tight joint with the lower side of the tube sheet B and at its lower end is spaced from the tube sheet B¹ to allow 40 the passage of the cooling medium around the lower edge of the partition 22 and thence upwardly between and around the tubes *g* and *g*¹, through the pass formed between the partitions 21, 22 and 23, which latter at its 45 lower end makes a tight joint with the tube sheet B¹ and at its upper end is spaced from the tube sheet B to form a space through which cooling medium flows over into the next pass formed by the partitions 21, 23 50 and 24, the cooling medium flowing downwardly in this pass between and around the tubes *u* and *u*¹, the partition 24 making a tight joint with the upper tube sheet B¹ and spaced from the lower tube sheet B¹ to form 55 a space around which the cooling medium flows into the next pass formed by the partitions 21, 24 and the wall of the shell A, the medium flowing upwardly in this pass between and around the tubes *s* and *s*¹ and 60 thence into the discharge conduit or passages 25, similar to the passages 20, and thence through the outlet port 26.

In taking the course described, it will be noted that cooling medium first flows downwardly in counter-current relation to the up-

ward discharge from the first stage ejectors through the tubes *i*, *i*¹, and thence upwardly in counter-current flow relation with respect to the downward discharge within the tubes *g*, *g*¹ of the first stage ejectors; thence downwardly in counter-current relation to the upward discharge from the second stage ejectors through the tubes *u*, *u*¹, and upwardly in counter-current flow relation to the downward discharge from the second stage 75 ejectors. This cooling medium, therefore, flows throughout its course in counter-current relation with respect to groups of tubes of first the inter condenser and then of the after condenser. 80

The second cooling medium, generally of lower temperature, as cold water from any suitable source, enters at the port or opening 27 into the uptake or vertically extending conduit or passage 28, whose wall at its lower end forms a tight joint with the tube sheet B¹ and which at its upper end falls short of or is spaced from the tube sheet B¹. Over the weir or upper edge 29 thus formed, the water flows downwardly in a pass 90 formed by the aforesaid partitions 21, the wall of the shell A and the partition 30, which at its upper edge forms a tight joint with the tube sheet B, and its lower end is spaced from the tube sheet B¹, as indicated in 95 Fig. 1, to allow passage of the water into the next pass. In descending the water passes between and around the tubes *p*, *p*¹ in counter-flow relation thereto, and thence upwardly in the next pass formed between the partitions 21, 21, 30 and 31, and in counter-current relation to the flow in the tubes *n*, *n*¹. The partition 31 at its lower end forms a tight joint with the tube sheet B¹ and is 100 spaced from the upper tube sheet B to allow 105 the water to flow over into the next pass disposed between the partitions 21, 21, 31 and 32. The water flows downwardly in this pass in concurrent relation to the discharge in the tubes *x* and *x*¹ of the after 110 condenser around the lower edge of the partition 32 and thence upwardly in the last pass formed between the partitions 21, 21, 32 and the shell A, in concurrent relation to the discharge through the tubes *z* and *z*¹, and 115 thence flowing over the weir edge 33 of the conduit or passage 34, whose wall at the lower end makes a tight joint with the tube sheet B¹. The water passing downwardly in the passage 34 is discharged through the 120 outlet port or opening 35.

The flow of the second cooling medium may be counter-current to the discharge through the tubes of the after condenser, if desired. This is readily accomplished, for example, by causing the upward discharge through the tubes *u*, *u*¹ to pass downwardly through the tubes *z*, *z*¹ and thence upwardly through the tubes *x*, *x*¹. This reverses the 125 relative directions of discharge through the 130

tubes x , z and x^1 , z^1 , so that with the second cooling medium passing as before described, it will flow counter to the discharges in the tubes of the after condensers. With the 5 change described, the vent or air-discharge port 15 would in such case be connected to a chamber in the end box F into which the tubes x and x^1 discharge upwardly, the partition 8 between chambers w and w^1 being 10 in such case omitted and a partition in alignment with the partition 8 disposed in the chamber, at present indicated at I, between the tube groups z and z^1 , and between the 15 two chambers so formed passages communicating with the chambers v and v^1 , similar to the passages k , k^1 between chambers j , m and j^1 , m^1 .

Accordingly, the second cooling medium first cools tubes of the inter condenser and 20 then of the after condenser, flowing counter-current to the discharge in the tubes of the inter condenser and concurrent with the discharge in the tubes of the after condenser. Furthermore, each of the two cooling media 25 cools first heat exchange structure of the inter condensers and then of the after condensers, the cooling media flowing counter-current to the discharge through the tubes of the inter condensers, and one of the cooling media flowing counter-current to the discharge through some of the tubes of the after condensers and the other cooling medium flowing concurrent with the discharge through the remainder of the tubes of the 30 after condensers.

The effect of the cooling media is to cool 35 the mixtures of motive steam and entrained air or other elastic fluid passing through the condenser tubes, effecting condensation of the motive steam and such other condensable vapors as may be exhausted with the air from the main condenser or another region or vessel.

The condensed motive fluid flows as condensate downwardly through the various condenser tubes into the corresponding chambers in the lower end box F¹. From the chambers h , h^1 and t , t^1 the condensate flows through the apertures 36, Fig. 11, in the lower portions of the partitions 6 into the pockets formed by the upstanding members 37, Figs. 10 and 11, rising to a level higher than the uppermost limit of the openings 36, whereby the condensate flowing 50 from the aforesaid chambers h , h^1 and t , t^1 flows over the upper edges of the members 37 into the chambers o , o^1 and y , y^1 , the liquid retained in the traps or pockets formed by the members 37 forming liquid seals permitting transfer of condensate as described, but preventing equalization of pressures between the chambers from and to which the condensate flows. This structure is of 55 special importance further in that in case no cooling medium is delivered through the

system comprising the inlet 27 and outlet 35, or in case its quantity is too small, uncondensed steam from the tubes of the inter-stage condensers is prevented from passing through the passages 36 or equivalents to 70 chambers communicating with the second stage ejectors. If uncondensed motive steam from the first stage did so reach the second stage ejectors, economy would be reduced, because of increased amount of motive fluid required in the second stage 75 ejectors.

The condensate flowing as aforesaid from the chambers h , h^1 into the chambers o , o^1 is mixed with the condensate collecting in 80 the chambers o , o^1 , the total condensate from one interstage condenser collected in chamber o then flowing into the drain channel 38, and the entire condensate from the other interstage condenser collecting in the chamber o^1 flows into the drain channel 39. With the channels 38 and 39 connect the condensate drain pipes 40 and 41, respectively, controlled by the valves 42 and 43, respectively, and then combining into the single 90 vacuum drain pipe 44, through which the condensate collected under vacuum within the structure is withdrawn to condensate-delivering control structure hereinafter referred to.

The total condensate from one after condenser collects in the chamber y flowing therefrom into the condensate drain channel 45; the total condensate from the other after condenser collects in the chamber y^1 , 100 from which it flows into the condensate drain channel 46, the chambers y and y^1 being at or near atmospheric pressure in case the outlet 15 discharges to atmosphere. Communicating with the channels 45 and 46 are the atmospheric condensate draw-off pipes 47 and 48, respectively, which join to form the single condensate drain pipe 49, 105 leading to the control structure hereinafter described.

It will be understood that my invention is not limited to the employment of the number of groups of tubes in the inter and after condensers as illustrated; any suitable one or more groups of tubes may be omitted, as 110 circumstances may permit or require.

In some instances, it may be desirable to omit the groups of tubes x , x^1 , z and z^1 , the same being those groups of tubes of the after-condensers which have hereinbefore 115 been described as cooled by the second cooling medium or cold water.

Furthermore, while I have spoken of cooling media of different temperatures, it will be understood that the matter of temperature is not a limitation of my invention, except where so expressed in the claims, and that cooling media, whatever their temperatures, from the same source or different 120 sources may be employed. Furthermore, 125 130

the condensate from the main condenser or the warmer cooling medium may be passed through the system whose inlet is at 27 and the outlet at 35, and the other medium or 5 cold water may be passed through the system whose inlet is at 19 and outlet at 26.

The cooling surface of each interstage condenser, comprising the groups of tubes g , i , n and p , or g^1 , i^1 , n^1 and p^1 , may be made 10 greater than or equal to, and is preferably made less than, the cooling surface of the associated after condenser comprising the groups of tubes s , u , x and z , or s^1 , u^1 , x^1 and z^1 .

15 The cooling surface of each interstage condenser cooled by the warmer cooling medium, as condensate from the main condenser entering, for example, at 19 and discharging at 26, may be made less than or 20 equal to, and is preferably made greater than, the cooling surface of the same interstage condenser cooled by the second cooling medium, as the cooler medium, entering, for example, at 27 and discharging at 35.

25 The cooling surface of each after condenser cooled by the condensate or warmer cooling medium, entering, for example, at 19 and discharging at 26, may be made less than or equal to, and is preferably greater than, that part of the cooling surface of the same after condenser cooled by the cold water or cooler cooling medium, entering, for example, at 27 and discharging at 35.

30 It is preferred also that the amount of 35 motive fluid, as steam, employed by the nozzle structure of an earlier or first stage ejector of a multi-stage combination be less than the amount of motive fluid, as steam, utilized by the nozzle structure of a later or second 40 stage ejector; and it is preferred further that the ratio of compression of an earlier or first stage ejector be greater than the ratio of compression of an associated later or second stage ejector, in accordance with 45 Letters Patent No. 1,283,593.

Referring to Figs. 12, 13 and 14, there is 50 illustrated, largely diagrammatically as concerns Fig. 12, a combination in which my hereinbefore described structure is utilizable. C represents a large main surface condenser for condensing the steam exhausted by a steam engine, turbine or the like, as customary in power plant practice. The exhaust steam enters at 50 and is 55 condensed within the shell C in well known manner, as by cooling water circulated through the condenser tubes, not shown. The condensate collects in the hot well H, and is from there drawn off by the condensate-removal pump J, driven by any suitable motor, not shown, the condensate being delivered to the feed water heater of the power plant or directly to the steam generators or boilers thereof, as may be desired. 60 65 In the example illustrated, however, the con-

densate is delivered by the pump J to the inlet 19 of one of the cooling media systems of the condenser K serving the ejectors, the condensate being discharged at 26 and then delivered to the feed water heater, boilers 70 or other destination.

From a point below or behind the baffle plate 51 within the main condenser C is the pipe connection 52, through which the air and uncondensable vapors or gases are withdrawn from the interior of the condenser C by the ejector apparatus for maintaining in the main condenser a suitably high vacuum in accordance with power plant practice. The air pipe 52 connects with a T 53, with 80 which connect the pipes 54 and 55, Fig. 5, controlled, respectively, by the valves 56 and 57, delivering to the suction chambers a and a^1 of the first stage ejectors E, E¹. By this arrangement, either pair of ejectors may be 85 employed alone, or both pairs may be utilized simultaneously, depending upon load conditions.

The second cooling medium, as cold water, is delivered by pipe 58, Fig. 12, to the pump 90 L, which forces it through the second cooling medium system of the condenser structure K, the water entering at 27 and discharging at 35 to any suitable destination.

The vacuum condensate drain pipe connection 44 delivers into the condensate-delivering trap or vacuum condensate drain control mechanism M, comprising a closed chamber in which is disposed the float 59, which rises and falls with change in level 100 of the vacuum condensate delivered by the pipe 44. The float 59 is disposed upon the end of a pivoted lever structure 60 terminating in the hollow sleeve or tube 61 fitting and rotating upon the inner tubular member or sleeve 62, the tubular members 61 and 62 having, respectively, the ports 63 and 64 moved to and from register with each other by movement of the float 59. As the vacuum condensate accumulates in the chamber M, 110 the float 59 rises, rotating the tubular member 61 in counter-clockwise direction, as viewed in Fig. 13, bringing the ports 63 and 64 into register with each other, and thereby 115 allowing escape from the chamber M of the vacuum condensate to the pipe 65, which discharges the condensate to any suitable destination, for example, into the hot well H into mixture with the condensate from the main condenser C, the higher vacuum 120 within the main condenser C serving to draw the condensate from the chamber M.

A second condensate drain control or automatic condensate-removal trap or mechanism O is provided for controlling the condensate removed at atmospheric, or, in general, higher pressure than that under which the vacuum condensate is delivered through the pipe 44 to the drain control M. The mechanism O may, as indicated, be conven- 125 130

iently attached to the mechanism M to form therewith a combined condensate drain control unit. The chamber O is vented to atmosphere at 66. The atmospheric condensate drain pipe 49 delivers condensate into the chamber O, in which is disposed a float 67 attached to a pivoted lever structure 68 attached to the tubular valve member 69 fitting and rotating upon the inner tubular member 70, the members 69 and 70 being provided, respectively, with ports 71 and 72 brought to register with each other as the float 67 rises, thereby allowing escape of the condensate through the pipe 73 to the pipe 15 65, mingling with the vacuum condensate and delivered therewith to the hot well H or to any desired or suitable destination.

For pressure equalizing purposes, particularly at pressures intermediate the pressure at the suction of the first stage ejector and atmospheric pressure, there is provided a pressure-equalizing pipe 74 connecting with the interior of the chamber M above the condensate level therein and extending to suitable chambers in the upper end box F. As illustrated in Figs. 5 and 6, the pipe 74 connects through branched pipes controlled by valves 75 and 76 with the ports 77 and 78, respectively, communicating with the chambers j, m and j¹, m¹, respectively, in the end box F. The pipe 74 therefore equalizes the pressure as between these chambers and the chamber M of the vacuum condensate drain control mechanism.

While the pressure-equalizing pipe 74 is illustrated as communicating with points intermediate the ends of the interstage condenser passages, it will be understood that it may communicate with any other of the chambers or at other points, as may be suitable or desirable. For example, pipe 74 may communicate with the chambers q, q¹ or r, r¹, or otherwise, as may be suitable or desirable. However, it is preferred that the pipe 74 communicate with those chambers which are adjacent, in the ejector discharge path or paths, the chambers in the box F¹, from which the vacuum condensate is withdrawn.

Irrespective of the hereinbefore described counter-current and concurrent flows as regards directions of flow of the fluids within and outside of the tubes, the cooling fluid entering at 19 flows counter-current to the first stage ejector discharge entering at the port 4, and counter-current to the second stage ejector discharge entering at the port 12 in the sense that the cooling fluid first comes into contact with heat exchange structure remote from the entry of each ejector discharge and later into contact with heat exchange structure adjacent the entry of ejector discharge. As regards the cooling medium entering at 27, it first flows counter-current to discharge of the first stage ejector entering at port 4, and then concurrent with

the second stage ejector discharge entering at 12, in the sense that the medium first comes into contact with heat exchange structure remote from the discharge entry port 4 and later with structure nearer the port 4, and thereafter in contact with heat exchange structure nearer the port 12 and thereafter with heat exchange structure more remote from the port 12.

What I claim is:

1. Combined ejector-condenser structure comprising an ejector, a condenser comprising a series of groups of tubes through which said ejector discharges in succession, a condenser shell common to and enclosing said groups of tubes, means for passing a cooling medium through said shell counter-current to a part of said groups of tubes, and means for passing a second cooling medium through said shell independently of said first named medium counter-current to another part of said groups of tubes.

2. Combined ejector-condenser structure comprising an ejector, a condenser comprising a series of groups of tubes through which said ejector discharges in succession, means for directing said discharge in opposite directions in the tube groups which are immediately adjacent each other in the series of groups, a condenser shell common to and enclosing said groups of tubes, means for passing a cooling medium through said shell counter-current to a part of said groups of tubes, and means for passing a second cooling medium through said shell independently of said first named medium counter-current to another part of said groups of tubes.

3. Combined ejector-condenser structure comprising an ejector, a condenser comprising a series of groups of tubes through which said ejector discharges in succession, a condenser shell common to and enclosing said groups of tubes, means for passing a cooling medium through said shell counter-current to a part of said groups of tubes first traversed by the ejector discharge, and means for passing a second cooling medium through said shell independently of said first named medium in contact with another part of said groups of tubes.

4. Combined ejector-condenser structure comprising an ejector, a condenser comprising a series of groups of tubes through which said ejector discharges in succession, means for directing said discharge in opposite directions in the tube groups which are immediately adjacent each other in the series of groups, a condenser shell common to and enclosing said groups of tubes, means for passing a cooling medium through said shell counter-current to a part of said groups of tubes first traversed by the ejector discharge, and means for passing a second cooling medium through said shell independently of

said first named medium in contact with another part of said groups of tubes.

5. Combined ejector-condenser structure comprising an ejector, a condenser comprising a series of groups of tubes through which said ejector discharges in succession, a condenser shell common to and enclosing said groups of tubes, means for passing a cooling medium through said shell counter-current to a part of said groups of tubes, 70 means for passing a second cooling medium of lower temperature through said shell independently of said first named medium counter-current to another part of said groups of tubes disposed in said series more 75 remote from said ejector, and a second ejector operating upon the discharge from said tubes.

10 current to a part of said groups of tubes, and means for passing a second cooling medium of lower temperature through said shell independently of said first named medium

15 counter-current to another part of said groups of tubes disposed in said series more remote from said ejector.

6. Combined ejector-condenser structure comprising an ejector, a condenser comprising a series of groups of tubes through which 20 said ejector discharges in succession, means for directing said discharge in opposite directions in the tube groups which are immediately adjacent each other in the series of groups, a condenser shell common to and enclosing said groups of tubes, means for passing a cooling medium through said shell counter-current to a part of said groups of tubes, and means for passing a second cooling 25 medium of lower temperature through said shell independently of said first named medium counter-current to another part of said groups of tubes disposed in said series more remote from said ejector.

7. Combined ejector-condenser structure comprising an ejector, a condenser comprising a series of groups of tubes through which said ejector discharges in succession, a condenser shell common to and enclosing said groups of tubes, means for passing a 30 cooling medium through said shell counter-current to a part of said groups of tubes, means for passing a second cooling medium through said shell independently of said first named medium counter-current to another part of said groups of tubes, and a second ejector operating upon the discharge from said tubes.

8. Combined ejector-condenser structure comprising an ejector, a condenser comprising a series of groups of tubes through which said ejector discharges in succession, a condenser shell common to and enclosing said groups of tubes, means for passing a cooling medium through said shell counter-current to a part of said groups of tubes first traversed by the ejector discharge, means for passing a second cooling medium through said shell independently of said first named medium in contact with another part of said groups of tubes, and a second ejector operating upon the discharge from said tubes.

9. Combined ejector-condenser structure comprising an ejector, a condenser comprising a series of groups of tubes through

which said ejector discharges in succession, a condenser shell common to and enclosing said groups of tubes, means for passing a cooling medium through said shell counter-current to a part of said groups of tubes, 70 means for passing a second cooling medium of lower temperature through said shell independently of said first named medium counter-current to another part of said groups of tubes disposed in said series more 75 remote from said ejector, and a second ejector operating upon the discharge from said tubes.

10. Combined ejector-condenser structure comprising an ejector, a condenser comprising a series of groups of tubes through which 80 said ejector discharges in succession, a second ejector operating upon the discharge from said tubes, tubes through which said second ejector discharges, a condenser shell 85 common to and enclosing all said tubes, and means for passing a cooling medium through said shell counter-current to all said tubes.

11. Combined ejector-condenser structure comprising an ejector, a condenser comprising a series of groups of tubes through which said ejector discharges in succession, means for directing said discharge in opposite directions in the tube groups which are immediately adjacent each other in the series of groups, a second ejector operating upon the discharge from said tubes, tubes through which said second ejector discharges, a condenser shell common to and enclosing all said tubes, and means for passing a cooling medium through said shell counter-current to all said tubes.

12. Combined ejector-condenser structure comprising an ejector, a condenser comprising a series of groups of tubes through which said ejector discharges in succession, a second ejector operating upon the discharge from said tubes, a second series of groups of tubes through which said second ejector discharges in succession, a condenser shell common to and enclosing said groups of tubes, and means for passing a cooling medium through said shell counter-current to all said groups of tubes.

13. Combined ejector-condenser structure comprising an ejector, a condenser comprising a series of groups of tubes through which said ejector discharges in succession, means for directing said discharge in opposite directions in the tube groups which are immediately adjacent each other in the series of groups, a second ejector operating upon the discharge from said tubes, a second series of groups of tubes through which said second ejector discharges in succession, 120 a condenser shell common to and enclosing said groups of tubes, and means for passing a cooling medium through said shell counter-current to all said groups of tubes.

14. Combined ejector-condenser structure 120

comprising an ejector, a condenser comprising a series of groups of tubes through which said ejector discharges in succession, a second ejector operating upon the discharge from said tubes, tubes through which said second ejector discharges, a condenser shell common to and enclosing all said tubes, means for passing a cooling medium through said shell in contact with a part of the groups of tubes through which said first named ejector discharges and in contact with said tubes through which said second ejector discharges, and means for passing through said shell independently of said cooling medium a second cooling medium in contact with another part of said groups of tubes through which said first named ejector discharges.

15. Combined ejector-condenser structure comprising an ejector, a condenser comprising a series of groups of tubes through which said ejector discharges in succession, means for directing said discharge in opposite directions in the tube groups which are immediately adjacent each other in the series of groups, a second ejector operating upon the discharge from said tubes, tubes through which said second ejector discharges, a condenser shell common to and enclosing all said tubes, means for passing a cooling medium through said shell in contact with a part of the groups of tubes through which said first named ejector discharges and in contact with said tubes through which said second ejector discharges, and means for passing through said shell independently of said cooling medium a second cooling medium in contact with another part of said groups of tubes through which said first named ejector discharges.

16. Combined ejector-condenser structure comprising an ejector, a condenser comprising a series of groups of tubes through which said ejector discharges in succession, a second ejector operating upon the discharge from said tubes, tubes through which said second ejector discharges, a condenser shell common to and enclosing all said tubes, means for passing a cooling medium through said shell in contact with a part of the groups of tubes through which said first named ejector discharges and in contact with said tubes through which said second ejector discharges, and means for passing through said shell independently of said cooling medium a second cooling medium in contact with another part of said groups of tubes through which said first named ejector discharges and in contact with said tubes through which said second ejector discharges.

17. Combined ejector-condenser structure comprising an ejector, a condenser comprising a series of groups of tubes through which said ejector discharges in succession,

a second ejector operating upon the discharge from said tubes, tubes through which said second ejector discharges, a condenser shell common to and enclosing all said tubes, means for passing a cooling medium through said shell in contact with a part of the groups of tubes through which said first named ejector discharges and in contact with said tubes through which said second ejector discharges, and means for passing through said shell independently of said cooling medium a second cooling medium of lower temperature in contact with another part of said groups of tubes disposed later in said series.

18. Combined ejector-condenser structure comprising an ejector, a condenser comprising a series of groups of tubes through which said ejector discharges in succession, a second ejector operating upon the discharge from said tubes, tubes through which said second ejector discharges, a condenser shell common to and enclosing all said tubes, means for passing a cooling medium through said shell in contact with a part of the groups of tubes through which said first named ejector discharges and in contact with said tubes through which said second ejector discharges, and means for passing through said shell independently of said cooling medium a second cooling medium of lower temperature in contact with another part of said groups of tubes disposed later in said series and in contact with said tubes through which said second ejector discharges.

19. Combined ejector-condenser structure comprising a plurality of ejectors, a condenser comprising a plurality of tubes for each ejector, said ejectors discharging through their respective tubes independently of each other, a condenser shell common to and enclosing all said tubes, and means for passing a cooling medium through said shell for cooling the tubes associated with the different ejectors.

20. Combined ejector-condenser structure comprising a plurality of ejectors, a condenser comprising a plurality of tubes for each ejector, said ejectors discharging through their respective tubes independently of each other, a condenser shell common to and enclosing all said tubes, and means for passing through said shell a plurality of cooling media independently of each other for cooling said tubes associated with the different ejectors.

21. Combined ejector-condenser structure comprising a plurality of ejectors, a condenser comprising a plurality of tubes for each ejector, said ejectors discharging through their respective tubes independently of each other, a condenser shell common to and enclosing all said tubes, means for passing through said shell a cooling

medium for cooling the tubes associated with the different ejectors, and means for passing a second cooling medium through said shell independently of said first named medium for cooling tubes associated with the different ejectors.

22. Combined ejector-condenser structure comprising a plurality of ejectors, a condenser comprising a plurality of tubes for 10 each ejector, said ejectors discharging through their respective tubes independently of each other, a condenser shell common to and enclosing all said tubes, and means for passing through said shell a cooling medium in divided streams for cooling tubes associated with the different ejectors.

23. Combined ejector-condenser structure comprising a plurality of ejectors, a condenser comprising a plurality of tubes for 20 each ejector, said ejectors discharging through their respective tubes independently of each other, a condenser shell common to and enclosing all said tubes, means for passing through said shell a cooling medium in divided streams for cooling tubes associated with the different ejectors, and means for passing through said shell independently of said medium a second cooling medium for cooling tubes associated with the different 25 ejectors.

24. Combined ejector-condenser structure comprising a plurality of ejector apparatus each comprising staged ejectors, a condenser comprising tubes into which each of said 30 ejectors discharges, a condenser shell common to and enclosing the tubes of all said ejector apparatus, and means for passing through said shell cooling medium for cooling the tubes of all said ejector apparatus.

40 25. Combined ejector-condenser structure comprising a plurality of ejector apparatus each comprising staged ejectors, a condenser comprising tubes into which each of said 45 ejectors discharges, a condenser shell common to and enclosing the tubes of all said ejector apparatus, and means for passing through said shell cooling medium in divided streams cooling, respectively, the tubes of the different ejector apparatus.

50 26. Combined ejector-condenser structure comprising a plurality of ejector apparatus each comprising staged ejectors, a condenser comprising tubes into which each of said 55 ejectors discharges, a condenser shell common to and enclosing the tubes of all said ejector apparatus, and means for passing a second cooling medium through said shell independently of said first named cooling medium for cooling the tubes of the 60 different ejector apparatus.

27. Combined ejector-condenser structure comprising a plurality of ejector apparatus each comprising staged ejectors, a condenser comprising tubes into which each of said 65 ejectors discharges, a condenser shell com-

mon to and enclosing the tubes of all said ejector apparatus, means for passing through said shell cooling medium in divided streams cooling, respectively, the tubes of the different ejector apparatus, and means for passing through said shell independently of said streams a second cooling medium cooling tubes of the different ejector apparatus. 70

28. Combined ejector-condenser structure 75 comprising an ejector, a condenser comprising a series of groups of tubes through which said ejector discharges in succession, means for cooling said tubes, chambers receiving condensate from different groups of tubes, means for drawing off condensate from one of said chambers, and means for delivering condensate from another of said chambers to said one of said chambers. 80

29. Combined ejector-condenser structure comprising an ejector, a condenser comprising a series of groups of tubes through which said ejector discharges in succession, means for cooling said tubes, chambers receiving condensate from different groups of tubes, means for drawing off condensate from one of said chambers, and a liquid-sealed trap through which condensate is delivered from another of said chambers to said one of said chambers. 95

30. Combined ejector-condenser structure comprising an ejector, a condenser comprising a series of groups of tubes through which said ejector discharges in succession, means for cooling said tubes, chambers receiving condensate from different groups of tubes, one of said chambers having a channel in which the condensate collects, and means for delivering condensate from another of said chambers to said one of said chambers. 100

31. Combined ejector-condenser structure comprising an ejector, a condenser comprising a series of groups of tubes through which said ejector discharges in succession, means for cooling said tubes, chambers receiving condensate from different groups of tubes, one of said chambers having a channel in which the condensate collects, and a liquid-sealed trap through which condensate is delivered from another of said chambers to said one of said chambers. 110

32. Combined ejector-condenser structure comprising ejector apparatus, condenser structure into which said ejector apparatus discharges, means for drawing off from said condenser structure condensates under different pressures, control mechanism comprising chambers to which said condensates are respectively delivered, and automatic means in each of said chambers for controlling withdrawal of condensate. 120

33. Combined ejector-condenser structure comprising ejector apparatus, condenser structure into which said ejector apparatus 130

- discharges, means for drawing off from said condenser structure condensates under different pressures, control mechanism comprising chambers to which said condensates are respectively delivered, and automatic means in each of said chambers for controlling withdrawal of condensate in response to changes in quantity of condensate therein.
- 5 10. 34. Combined ejector-condenser structure comprising ejector apparatus, condenser structure into which said ejector apparatus discharges, means for drawing off from said condenser structure condensates under different pressures, control mechanism comprising chambers to which said condensates are respectively delivered, automatic means in each of said chambers for controlling withdrawal of condensate, and a pressure-equalizing connection between one of said chambers and a region in said condenser at a pressure lower than the pressure of discharge from said condenser. 70
- 15 11. 34. Combined ejector-condenser structure comprising ejector apparatus, condenser structure into which said ejector apparatus discharges, means for drawing off from said condenser structure condensates under different pressures, control mechanism comprising chambers to which said condensates are respectively delivered, automatic means in each of said chambers for controlling withdrawal of condensate, and means for 75 conducting the condensates away from said chambers in mixture with each other.
- 20 12. 35. Combined ejector-condenser structure comprising ejector apparatus, condenser structure into which said ejector apparatus discharges, means for drawing off from said condenser structure condensates under different pressures, control mechanism comprising chambers to which said condensates are respectively delivered, automatic means in each of said chambers for controlling withdrawal of condensate, and means for connecting said chambers with a region of lower pressure whereby the condensates are withdrawn from said chambers. 80
- 25 13. 35. Combined ejector-condenser structure comprising ejector apparatus, condenser structure into which said ejector apparatus discharges, means for drawing off from said condenser structure condensates under different pressures, control mechanism comprising chambers to which said condensates are respectively delivered, automatic means in each of said chambers for controlling withdrawal of condensate, and means for connecting said chambers with a region of lower pressure whereby the condensates are withdrawn from said chambers. 85
- 30 14. 36. Combined ejector-condenser structure comprising ejector apparatus, condenser structure into which said ejector apparatus discharges, means for drawing off from said condenser structure condensate under a pressure less than atmospheric pressure, means for drawing off from said condenser structure a second condensate under higher pressure, control mechanism comprising chambers to which said condensates are respectively delivered, and automatic means in each of said chambers for controlling withdrawal of condensate. 90
- 35 15. 37. Combined ejector-condenser structure comprising ejector apparatus, condenser structure into which said ejector apparatus discharges, means for drawing off from said condenser structure condensate under a pressure less than atmospheric pressure, means for drawing off from said condenser structure a second condensate under higher pressure, control mechanism comprising chambers to which said condensates are respectively delivered, automatic means in each of said chambers for controlling withdrawal of condensate. 95
- 40 16. 38. Combined ejector-condenser structure comprising ejector apparatus, condenser structure into which said ejector apparatus discharges, means for drawing off from said condenser structure condensate under a pressure less than said first named pressure whereby the condensates are withdrawn from said chambers. 100
- 45 17. 39. Combined ejector-condenser structure comprising multi-stage ejectors, inter and after condensers therefor, means for cooling said inter condenser by different cooling media, the cooling surface of the inter condenser being less than the cooling surface of the after condenser, and the portion of cooling surface of the inter condenser cooled by one of said media being greater than the portion of cooling surface of said inter condenser cooled by another of said cooling media. 105
- 50 18. 40. Combined ejector-condenser structure comprising multi-stage ejectors, inter and after condensers therefor, means for cooling said inter condenser by cooling media of different temperatures, the cooling surface of the inter-condenser being less than the cooling surface of the after condenser, and the portion of cooling surface of the inter condenser cooled by the cooling medium of higher temperature being greater than the portion of the cooling surface of the inter condenser cooled by a cooling medium of lower temperature. 110
- 55 19. 41. Combined ejector-condenser structure comprising multi-stage ejectors, inter and after condensers therefor, means for cooling an after condenser by different cooling media, the portion of the cooling surface of said after condenser cooled by one of said media being greater than the portion of cooling surface of said after condenser cooled by another of said media. 115
- 60 20. 42. Combined ejector-condenser structure comprising multi-stage ejectors, inter and after condensers therefor, means for cooling an after condenser by cooling media of different temperatures, the portion of the cooling surface of said after condenser cooled by the condensate of higher temperature being greater than the portion of the cooling surface of said after condenser cooled by a cooling medium of lower temperature. 120
- 65 21. 43. Combined ejector-condenser structure comprising multi-stage ejectors, inter and after condensers therefor, the cooling surface of an inter condenser being less than the cooling surface of an after condenser, means for cooling said after condenser by different cooling media, the portion of the cooling surface of said after condenser 125
- 70 22. 44. Combined ejector-condenser structure comprising multi-stage ejectors, inter and after condensers therefor, the cooling surface of an inter condenser being less than the cooling surface of an after condenser, means for cooling said after condenser by different cooling media, the portion of the cooling surface of said after condenser 130

cooled by one of said media being greater than the portion of the cooling surface of said after condenser cooled by another of said media.

- 6 44. Combined ejector-condenser structure comprising multi-stage ejectors, inter and after condensers therefor, the cooling surface of an inter condenser being less than the cooling surface of an after condenser, means 60
 10 for cooling said after condenser by cooling media of different temperatures, the portion of the cooling surface of said after condenser cooled by the cooling medium of higher temperature being greater than the part of 65
 15 the cooling surface of said after condenser cooled by a cooling medium of lower temperature.
 45. Combined ejector-condenser structure comprising multi-stage ejectors, inter and 70
 20 after condensers therefor, the cooling surface of an inter condenser being less than the cooling surface of an after condenser, means for cooling said inter condenser with different cooling media, means for cooling 75
 25 said after condenser with said different cooling media, the portion of the cooling surface of said after condenser cooled by one of said cooling media being greater than the part of the cooling surface of said after condenser 80
 30 cooled by another of said cooling media.

46. Combined ejector-condenser structure comprising multi-stage ejectors, inter and after condensers therefor, the cooling surface of an inter condenser being less than 85
 35 the cooling surface of an after condenser, means for cooling said inter condenser with cooling media of different temperatures, means for cooling said after condenser by said cooling media of different temperatures, 90
 40 the portion of the cooling surface of said after condenser cooled by the cooling medium of higher temperature being greater than the portion of the cooling surface of said after condenser cooled by a cooling 95
 45 medium of lower temperature.

47. Combined ejector-condenser structure comprising multi-stage ejectors, inter and after condensers therefor, means for cooling said inter and after condensers by different 100
 50 cooling media, the portion of the cooling surface of said inter condenser cooled by one of said cooling media being greater than the portion of the cooling surface of said inter condenser cooled by another of 105
 55 said cooling media, and the portion of the

cooling surface of said after condenser cooled by one of said cooling media being greater than the portion of the cooling surface of said after condenser cooled by another of said cooling media. 60

48. Combined ejector-condenser structure comprising multi-stage ejectors, inter and after condensers therefor, means for cooling said inter and after condensers by cooling media of different temperatures, the portions of the cooling surfaces of said inter and after condensers cooled by a cooling medium of higher temperature being greater than the portions of the cooling surfaces of said inter and after condenser cooled by a 70 cooling medium of lower temperature.

49. Combined ejector-condenser structure comprising an ejector, tubes into which said ejector discharges, a condenser shell enclosing said tubes, a conduit delivering adjacent 75 one end of said shell into the space between said tubes, and means for introducing cooling medium into said conduit at its end adjacent the other end of said shell.

50. Combined ejector-condenser structure 80 comprising an ejector, tubes into which said ejector discharges, a condenser shell enclosing said tubes, a conduit receiving at its end adjacent one end of said shell cooling medium from the space between said tubes, and 85 a discharge outlet for the cooling medium communicating with said conduit at its end adjacent the other end of said shell.

51. Combined ejector-condenser structure 90 comprising ejectors, groups of tubes into which said ejectors independently discharge, a condenser shell enclosing said groups of tubes, a conduit on said shell having discharge openings adjacent the different groups of tubes, and means for conducting 95 cooling medium to said conduit.

52. Combined ejector-condenser structure comprising ejectors, groups of tubes into which said ejectors independently discharge, 100 a condenser shell enclosing said groups of tubes, a conduit on said shell having ports adjacent to different groups of tubes for receiving cooling medium from between said tubes, and a discharge port communicating 105 with said conduit.

In testimony whereof I have hereunto affixed my signature this 25th day of October, 1922.

ROBERT SUCZEK.
